UNITED STATES PATENT OFFICE.

ARTHUR F. BLECHSCHMIDT, OF CONNERSVILLE, INDIANA.

BURGLAR-PROOF SAFE.

1,097,076.

Specification of Letters Patent.

Patented May 19, 1914.

Application filed May 10, 1911. Serial No. 626,282.

To all whom it may concern:

Be it known that I, ARTHUR FRED BLECHSCHMIDT, citizen of the United States, residing at Connersville, in the county of Fayette 5 and State of Indiana, have invented certain new and useful Improvements in Burglar-Proof Safes, of which the following is a specification.

This invention relates to improvements in 10 safes.

The object of my invention consists in providing a resilient bolt seat in a safe arranged to cushion the shock of an explosive charge taking place in the interior of the 15 safe and engaging the bolts for locking the door of the safe. By means of my invention when the explosion takes place the door is forced slightly out of its seat to allow the gases to make their exit.

With the above and other objects in view 20 my invention consists in the combination, arrangement, and details of construction shown in the drawings and then more particularly pointed out in the appended claims.

In the drawings a side elevation in section 25 is shown of a safe provided with my invention.

In the drawings A designates a safe of the round type, which may be of any approved 30 construction. A standard 1 supports the safe 2.

B is the door of the safe and is in the form 35 of a truncated cone and seats in a similarly shaped opening in the safe. This door is connected to a hinge or swinging yoke 3.

4 is a shaft carrying at each end an eccentric presser bar 5, which works in an eccentric box 6 made to receive it. These presser bars serve to jam the door in tightly as 40 is known to those skilled in the art. The worm 4^a is mounted on shaft 4 and engages a worm wheel 7^a on the shaft of hand wheel 7.

8 represents the interior of the safe.

The door is in the shape of a truncated cone and is fitted in a correspondingly shaped opening in the safe.

Inside the safe a plurality of housings 10 are formed in the door seat around the door 50 B, said door extending beyond the springs

11, located in and retained in position by, the walls 9 of said housings 10. These springs 11 project out of the housings 10 and are engageable by the radially-extending bolts 12 suitably mounted on said door B 55 and bearing against said springs when the door is locked. The bolts 12 are usually operated by a bolt-motor 13, controlled by the time lock 14. It is necessary to retract the bolts 12 before the door can be opened. 60

If an explosive is let off inside the safe the gases resulting therefrom will force the door B out of its seat. The gases of explosion would throw the door B out of its opening a slight distance, as far as said 65 springs would permit, and the bolts 12 carried by the door would compress said springs to allow of such movement of said door. In this way there will be clearance around the door from the adjacent surface 70 of the safe, and the explosive gases will escape out of the safe through the space thus provided. The springs will be made of stout spring metal so as to make it difficult for the door to be pulled out of its opening 75 against the tension of springs 11, by applying an external agency.

I do not limit myself to the exact details of construction disclosed as modifications may be made falling within the purview of 80 the appended claims.

I claim—

1. In a safe, the combination of a door, a plurality of housings formed in the door seat around said door, springs located in 85 said housings and projecting therefrom, and radially-extending locking bolts carried by said door and bearing against said springs.

2. A safe having a door and casing therefor, bolts for holding said door locked and 90 means upon which said bolts are adapted to seat whereby said door is held resiliently seated, said means consisting of springs, said springs being seated on said casing.

In testimony whereof I affix my signature 95 in presence of two witnesses.

ARTHUR F. BLECHSCHMIDT.
